(57) CLAIM

I claim the ornamental design for a cocktail smoker insert, as shown and described.

DESCRIPTION

FIG. 1 is a top perspective view of a cocktail smoker insert showing my new design;

FIG. 2 is a bottom perspective view thereof;

FIG. 3 is a right-side elevation view thereof, the left-side, front, and back views being identical;

FIG. 4 is a top plan view thereof;

FIG. 5 is a bottom plan view thereof; and,

FIG. 6 is a perspective view thereof, showing the cocktail smoker insert in use.

The broken lines in FIG. 6 showing a cocktail smoker and glass are included for the purpose of illustrating environmental structure and form no part of the claimed design.
